UNITED STATES PATENT OFFICE

2,590,505

INTERLOCK FOR ELECTRICAL CONNECTORS

Otte Carlsen, Monrovia, Calif.

Application August 18, 1949, Serial No. 109,607

1 Claim. (Cl. 173—343)

1

This invention relates to new and useful improvements and structural refinements in electrical connectors, particularly those commonly employed at the end of an attachment cord for receiving an attachment plug at the adjacent end of a connecting cord, the principal object of the invention being to firmly and securely hold the attachment plug so as to prevent undesired separation of the two cords.

This object is achieved by the provision of the instant connector which embodies in its construction means for frictionally engaging and clamping the prongs of an attachment plug, an important feature of the invention, therefore, residing in the structure of the connector and in the clamping means whereby the frictional engagement or gripping of the attachment plug prongs is facilitated.

Some of the advantages of the invention lie in its simplicity of construction, in its dependable operation, and in its adaptability to economical manufacture.

With the above more important objects and features in view and such other objects and features as may become apparent as this specification proceeds, the invention consists essentially in the arrangement and construction of parts as illustrated in the accompanying drawings, in which:

Figure 1 is a perspective view of the invention;
Figure 2 is a vertical sectional view thereof;

Figure 3 is a horizontal cross-sectional view, taken substantially in the plane of the line 3—3 in Figure 2; and

Figure 4 is a group perspective view of one of the prong-contacting members and terminals used in the invention.

Like characters of reference are employed to designate like parts in the specification and throughout the several views.

Referring now to the accompanying drawings in detail, the invention consists of an electrical connector designated generally by the reference character 10, the same embodying in its construction an elongated body 12 comprising a main body member 14 and an extension 16, both of which are preferably formed from insulating material such as rubber, or the like.

The body members 14, 16 are separably connected together by an interlocking flange and groove arrangement 18, it being understood that the extension 16 is sufficiently resilient to permit the interlocking flange and groove to be separated for the purpose of applying the entire connector to an extension cord 20, or for purposes of inspection, or the like.

It is to be also noted that the body extension 16 is hollow, as indicated at 22, while the main body portion 14 is provided with a plurality of slots 24 which communicate with the interior of

2

the extension 16 and are adapted to receive the prongs 58 of a conventional attachment plug (not shown).

A prong-contacting member or strap 26 is rigidly secured in one side wall of each of the slots 24 by being embedded in the main body portion 14 at manufacture, and the inner ends of the members 26 are provided in opposite longitudinal edges thereof with transversely aligned notches 28 to accommodate a substantially U-shaped keeper 30 which is secured to the associated contact member by a terminal screw 32.

The actual wires 34 of the conductors 20 extend into the hollow interior 22 of the body extension 16 and are clamped between the members 26 and the keepers 30, whereby undesired separation of the wires from the contact members is effectively prevented.

The essence of novelty of the invention resides in the provision of a plurality of prong-clamping elements or blocks 36 which are slidable inwardly and outwardly in suitable recesses 38 formed in the main body portion 14, it being noted that the outer circumferential surface of the body portion 14 is provided with an annular groove or channel 40 from which the recesses 38 extend inwardly and communicate with the slots 24, as is best shown in Figure 2.

The groove 40 is intended to accommodate an expandible and contractible clamp 42 which simply assumes the form of a substantially circular band provided at the ends thereof with a pair of spaced, opposing ears 44, 46, the former ear being screw threaded to receive a clamping stud 48, while the latter ear is provided with an aperture through which the stud may freely slide, as will be clearly apparent from Figure 3.

One end of the stud 48 is equipped with an eye 50, which in turn, is pivotally connected as at 52 to a cam 54 which is operatively engageable with the adjacent portion of the clamp band 42 and is provided with a suitable finger piece 56.

When the invention is placed in use, the prongs of the attachment plug are simply inserted in the slot 24, as indicated by the phantom lines 58 in Figure 2, so that they electrically engage the contact members 26, during which operation the cam 54 is, of course, in an open position as indicated at 60 in Figure 3. In this position the clamp 42 is expanded so as to facilitate insertion of the prongs but after the prongs are inserted the cam 54 is pressed toward the clamp 42 by means of the finger piece 56, so that the clamping band is contracted and the blocks 36, which are engageable by the clamping band, are pressed inwardly so that the prongs 58, in turn, are frictionally engaged with the contact members 26. It will be apparent from the foregoing that in this manner undesired separation of the connector and attachment plug will be prevented, but,

needless to say, separation thereof will be readily facilitated by simply opening the cam 54 of the clamp 42.

It is believed that the advantages and use of the invention will be clearly apparent from the foregoing disclosure and, accordingly, further description thereof at this point is deemed unnecessary.

Having described the invention, what is claimed as new is:

In an electrical connector, the combination of an elongated body provided in one end thereof with a set of longitudinally extending slots having inner and outer opposing walls, a set of flat conductor members provided at the inner walls of the respective slots and spaced from the outer walls whereby to receive therebetween the prongs of an attachment plug, the side wall of said body being formed adjacent the slotted end thereof with a perimetric keeper groove and with a set of recesses extending inwardly from said groove to the outer walls of the respective slots, a set of prong clamping blocks slidable inwardly and outwardly in said recesses, an expandible and

contractible band positioned in said groove in engagement with outer ends of said blocks, the ends of said band being provided with a pair of spaced out-turned ears, an adjustable fastening element attached to one ear and extending slidably through the second ear, an eye on said element adjacent said second ear, and a cam pivoted to said eye and operatively engaging said band, whereby the latter may be contracted to frictionally engage inner ends of said blocks with prongs inserted in said slots.

OTTO CARLSEN.
